ROCKABLE INNER JAW WRENCH
Max Barnett, Brooklyn, N. Y.
Application May 15, 1946, Serial No. 669,812

8 Claims.

(Cl. 81—93)

1
The subject matter of this invention relates to a functionally and structurally improved wrench having a tilting and adjustable inner jaw.

One object of the invention resides in the provision of novel means to permit the jaws of the wrench to be quickly and automatically released from an article turned by the wrench however without binding of the jaws of the wrench against the article. A specific object is realized in the provision of a serviceable and effective wrench having an adjustable convexedly contoured seat upon which the inner jaw of the wrench is automatically and tiltably displaced on applying the wrench to an article to be adjusted by the latter, the inner jaw carrying a shank embracing saddle having a pin and slot connection with the seat, and the saddle embodies means for slidably guiding a spring controlled yoke straddling the shank of the wrench. Other important objects and advantages will appear from the following detailed specification taken with the accompanying drawings wherein

Fig. 1 is a side elevational view of the wrench according to my invention, and illustrates the jaws separated and awaiting reception of a pipe to be grasped.

Fig. 2 is a fragmentary view of Fig. 1 depicting the jaws initially gripping a pipe interposed therebetween.

Fig. 3 is a view similar to Fig. 2 but showing the wrench firmly clamping the pipe and about to be released therefrom for its retractive swing.

Fig. 4 is a front view on the line 4—4 of Fig. 1.

Figs. 5 and 6 are horizontal sectional views on the lines 5—5 and 6—6 of Fig. 1.

Fig. 7 is a perspective view of the rockable jaw.

Fig. 8 is a fragmentary perspective view of the adjustable cam shaped support or mount for the lower rockable jaw, and

Fig. 9 is a sectional view on the line 9—9 of Fig. 2.

Illustrative of the embodiment disclosed, the wrench is generally denoted W and comprises an upper toothed jaw 10 fixedly retained by the overhanging head 11 merged with a vertically disposed shank 12. Extending forwardly of the shank and preferably integral therewith is a socket-containing member 13 having a concaved portion or annular seat 14 communicating with a tapered bore 15.

Seat 14 is adapted to receive and position an annular projection 16 depending from a knurled and hollow, internally threaded cylindrical nut 17, threadably engaging an externally threaded stud 18 which slidably projects through a bore

19 of the annular projection 16 and into the bore 15. It follows that if ring or nut 17 is rotated or manipulated on the threaded stud 18, the latter will be elevated or lowered, depending upon the direction of rotation.

Projecting upwardly from socket containing member 13 and integral therewith is an extension 20 having an inwardly overhanging portion 21 provided with a depending lip 22 receivable in an annular groove 23 in nut 17 to limit displacement of the manipulating nut in a direction away from seat 14.

Appropriately fastened to the externally threaded stud 18 is a cam shaped block or support 24 having spaced and parallel sides 25 normal to a front plane surface 26. Sides 25 are rabbeted to define grooves 27, thus characterizing a rearwardly extending reduced portion or boss 28 closely and movably straddled by rounded terminals 29 of spaced legs 30 of a U-shaped yoke 30A spaced from and straddling opposite sides 31 of shank 12.

Referring again to the mount or block 24, its upper surface 32 is convexed from front to back and from side to side, that is both longitudinally and transversely, and in effect constitutes a cam face 32 on which an inclined or biased face 33 of a lower toothed jaw 34 may be tilted or rocked.

Forming a part of the tiltable jaw 34 is a depending and reduced projection or lip 35 having spaced parallel sides 36 in vertical alignment with the spaced sides 25 of the cam block or support 24 on which the inclined and plane face 33 of the rockable jaw is seated.

Extending laterally beyond the sides 36 of the pivotable or rockable jaw 34 are shoulders 37 seated on front portions 38 of spaced arms 39 of a U-shaped floating saddle, generally designated 40, having an intervening web 41 provided with a recess 42 (Fig. 6) for receiving and positioning one end of a normally expanded helicoidal spring 43 having its other end surrounding a suitable fixed pin 44 extending from a web 45 of the yoke 30A.

Fixedly fastened to the spaced sides 36 of the tiltable jaw 34 by a headless rivet 46 are the forward portions 38 of the spaced sides 39 of the floating saddle 40 which closely and slidably straddles the spaced sides 30 of the yoke 30A which in turn loosely but slidably guides shank 12, there being ample clearance between the latter and the sides of the yoke 30A as illustrated in Fig. 6.

Spring 43 normally holds the curved ends 29 yieldingly against transverse vertical faces 47

defined by the notches 27 of the cam shaped support 24. The jaw 34 may be said to rock, slide or tilt relative to cam support 24.

Removably straddling shank 12 are spaced ears or lugs 48 projecting rearwardly from the rockable lower jaw 33. Undesirable separation of the latter from the cam face 32 of the mount 24, is prevented by a pin 50 which extends into an inclined slot 51 in one of the legs 39 of the floating saddle 40, slot 51 being appreciably larger than the diameter of the pin 50 so as to permit adequate clearance.

In Fig. 1, the jaws are in open position to receive a pipe. In such relation, tail or depending portion 35 is against the front stop face 26 of the cam support 24 and the normally expanded spring 43 causes the arcuate ends 29 of the inner guide or yoke 30A to yieldingly bear against transversely disposed shoulders 47 of the mount 24. The saddle 40 is now substantially horizontal and the pin 50 is towards the lower end of the inclined slot 51 in the saddle 40 which as previously stated is anchored by rivet 46 to the rockable jaw 34.

Even though jaws 10 and 34 are separated, the latter is tilted relative to the mount 24 on the insertion of the pipe into the wrench. To this end, a forwardly directed finger thrust is applied to the web 41 of the saddle 40. Since the lower jaw 34 is carried by the saddle, this jaw will be shifted bodily away from the shank 12 and its forward end will also be tilted downwardly as indicated in Fig. 2 at which time projections 48 leave shank 12, and the lip 35 of jaw 34 is displaced from the vertical stop face 26 of the mount. At this time pipe C is inserted into the wrench. Thereafter, finger pressure is removed from saddle 40 and the latter automatically retracts due to the action of spring 43, in turn causing the inclined jaw 34 to retract and grip the pipe, which is now firmly retained by the jaws and in position to be turned. Subsequently, a rotational thrust in a direction towards socket 13 is applied to the handle 52 of shank 12. This action causes jaw 34 to be pivoted or tilted upwardly (Fig. 3), thus elevating its forward end towards the pipe, hence more firmly gripping the latter as the pipe is turned by the wrench. Since jaw 34 and the saddle are secured together, movement of one correspondingly displaces the other and consequently when the pipe is grasped and turned, saddle 40 will be appreciably inclined or biased relative to the shank and of course against the resistance of spring 43 which has been compressed in that rear face of shank 12 has shifted yoke 30A rearwardly, the sides 39 of the yoke being slidably guided in the recesses 53 in the spaced sides or legs 39 of the saddle. Having turned the pipe, the wrench may be quickly automatically released. This is accomplished by merely rotating the wrench in a direction counter to that required for turning the pipe or article P. Thereafter if desired the wrench may again receive the required thrust for turning the pipe.

Immediately upon the release of gripping pressure on the pipe the lower jaw 34 automatically is retracted to its normal position illustrated in Fig. 1 due to the action of the normally expanded spring 43, thus also restoring the tiltable saddle and the slideable yoke 30A to their normal positions. By the arrangement disclosed, it is quickly possible to release the jaws to permit manual rotational retraction of the wrench after the pipe has been turned how-

ever without binding the jaws against the pipe.

Pin 50 carried by mount 24 and slot 51 of the saddle constitute a loose connection permitting the saddle to be readily displaced against the action of spring 43 and the arcuate cam face 32 of the mount permits the jaw 34 to be tilted transversely and longitudinally of the mount to compensate for any irregularities in the object or article to be gripped and turned by the wrench.

Of course apart from being adapted to be tiltably displaced relative to the mount 24, the tilttable jaw is also adapted to be moved forwardly away from the stop face 26 upon the manipulation of the saddle 40. Upon removal of manipulating pressure, the saddle automatically retracts again causing lugs 48 to removably interlock with the sides of shank 12. For purposes of specification jaw 34 and the saddle 40 may be said to be a bell crank lever tiltably and loosely guided on the mount and relative to shank 12 of the wrench.

Various changes may be made in details of construction and arrangement of parts without departing from the spirit of the invention or sacrificing any of the advantages thereof inherent therein.

I claim:

1. In a wrench for turning an article, a shank 30 having an overhanging head including a fixed jaw, a shifttable jaw, a mount having a top convex face tiltably sustaining said shifttable jaw, a nut for displacing said mount to move said shifttable jaw towards or away from said fixed jaw, a U-shaped saddle having spaced sides loosely straddling and extending beyond front and rear faces of said shank and said sides embodying front corresponding portions straddling and fixed to said shifttable jaw, pin and slot connecting means between said sides and mount, and spring means interposed between said shank and saddle for normally urging said shifttable jaw in a direction towards said shank, said shifttable jaw on gripping of said article by said jaws tilting relative to said mount whereby said jaws firmly but disengageably clamp said article and tilting saddle relative to said shank.

2. In a wrench for turning an article, a shank having an overhanging head including a fixed jaw, a mount having an arcuate cam face and depending threaded means, a shifttable jaw embodying an inclined rectilinear wall seated on said face, a nut cooperating with said threaded means for displacing said mount to move said shifttable jaw towards or away from said fixed jaw, a saddle loosely straddling said shank and having spaced sides secured at their forward ends to said shifttable jaw, a pin and slot connection between said mount and saddle, and spring means cooperating with said saddle for yieldably urging said shifttable jaw towards said shank.

3. In a wrench for turning an article, a shank having an overhanging head including a fixed jaw, a mount having an arcuate cam face and depending threaded means, a shifttable jaw embodying an inclined rectilinear wall seated on said face, a nut cooperating with said threaded means for displacing said mount to move said shifttable jaw towards or away from said fixed jaw, a U-shaped saddle loosely straddling said shank and having spaced sides secured at their forward ends to said shifttable jaw, a yoke slidably guided by said sides, a pin and slot connection between said mount and saddle, and helicoidal

spring means cooperating with said yoke and saddle for yieldably urging said shiftable jaw towards said shank.

4. In a wrench for turning an article, a shank having an overhanging head including a fixed jaw, a mount having a curved cam face disposed longitudinally thereof, a shiftable jaw embodying an inclined rectilinear wall seated on said face, adjustable means carrying said mount and comprising a threaded member and an internally threaded rotatable manipulator for displacing said mount to move said shiftable jaw towards or away from said fixed jaw, a U-shaped tilttable saddle loosely straddling said shank and having spaced sides secured at their forward ends to said shiftable jaw and embodying recessed means, a yoke slidably guided by said recessed means and tiltably straddling said shank, a pin and slot connection between said mount and saddle, and helicoidal spring means cooperating with said yoke and saddle for yieldably urging said shiftable jaw towards said shank.

5. In a wrench for turning an article, a shank having an overhanging head including a fixed jaw, a mount having a top arcuate cam face and a rearwardly disposed portion reduced in width, a shiftable jaw embodying an inclined rectilinear wall seated on said face so as to permit tilting of said shiftable jaw, means interposed between said mount and shank for linearly displacing said mount to move said shiftable jaw towards or away from said fixed jaw, a saddle loosely straddling said shank and having spaced sides secured at their forward ends to said shiftable jaw and including recess means, a yoke having spaced sides slidably guided in said recess means and tiltably straddling said shank and reduced portion, a pin and slot connection between said mount and saddle, and helicoidal spring means cooperating with said yoke and saddle for yieldably urging said shiftable jaw towards said shank.

6. In a wrench for turning an article, a shank having an overhanging head including a fixed jaw, a mount having an upper convex face and a rearwardly disposed portion reduced in width, a shiftable jaw embodying an inclined rectilinear wall seated on said face so as to permit tilting of said shiftable jaw, said shiftable jaw having rearwardly disposed spaced lugs, means interposed between said mount and shank for linearly displacing said mount to move said shiftable jaw towards or away from said fixed jaw, a saddle loosely straddling said shank and having spaced sides secured at their forward ends to said shiftable jaw and including recess means, a yoke having spaced sides slidably guided in said recess means and tiltably straddling said shank and reduced portion, a pin and slot connection between said mount and saddle, and helicoidal spring means cooperating with said yoke and saddle for yieldably urging said shiftable jaw towards said shank for removably interlocking said lugs with the latter.

7. In a wrench for turning an article, a shank

having an overhanging head including a fixed jaw, a mount having an upper convex cam face and a rearwardly disposed portion reduced in width, a shiftable jaw embodying an inclined rectilinear wall seated on said face so as to permit tilting of said shiftable jaw, means comprising a threaded stud depending from said mount and an internally threaded rotatable nut for linearly displacing said stud to move said shiftable jaw towards or away from said fixed jaw, a saddle loosely straddling said shank and having spaced sides secured at their forward ends to said shiftable jaw and including recess means, a yoke having spaced sides slidably guided in said recess means and tiltably straddling said shank and reduced portion, a pin and slot connection between said mount and saddle, helicoidal spring means cooperating with said yoke and saddle for yieldably urging said shiftable jaw towards said shank, a socket for receiving said stud and carried by said shank and including an annular seat, annular means depending from said nut and removably positioned on said seat, and stop means to limit displacement of said nut away from said seat.

25 8. In a wrench for turning an article, a shank having a head including a fixed jaw, a shiftable jaw under said fixed jaw, a mount having a top convex face curved both transversely and longitudinally thereof and tiltably sustaining said shiftable jaw, means interposed between said mount and shank for adjustably displacing said mount to move said shiftable jaw towards or away from said fixed jaw, a saddle having spaced sides connected to said shiftable jaw and loosely straddling said shank for bodily displacing said shiftable jaw forwardly of said shank, a yoke straddling said shank and having spaced legs slidably guided by and between said sides, said yoke having a web portion connecting said legs, and normally expanded helicoidal spring means cooperating with said saddle and web portion for retracting said shiftable jaw pursuant to forward and tilttable displacement thereof relative to said shank, said saddle being tilttable relative to said shank for displacing said yoke relative to said sides to compress said spring means.
